MANUFACTURE OF KNITTED GOODS

Theodor Krasselt, Reuth v/ Neumark, Germany,
assignor of four-fifths to Maurice Presburg,
Paris, France, and one-fifth to George Angus
& Company Limited, Newcastle-on-Tyne, Eng-
land, a British company

Application May 16, 1936, Serial No. 80,154
In Germany June 6, 1935

1 Claim. (Cl. 66—125)

This invention relates to the manufacture of knitted articles from asbestos yarn which, as sold in the trade, consists of fibres of very short staple length.

5 It has not hitherto been possible to knit asbestos yarn on a machine owing to the fact that the yarn tears so readily, and it has consequently been necessary to manufacture asbestos articles of clothing and the like either by hand knitting or by weaving. Hand knitted asbestos gloves and the like are, however, very expensive to make, and woven asbestos clothing has the disadvantage that it is extremely stiff and rigid and seriously hampers the movements of the wearer.

10 Moreover woven asbestos clothing is uncomfortable to wear because of its close texture which prevents evaporation from the body. Again, when gloves and similar articles are made from woven asbestos fabric it is necessary to sew together the 15 edges of the fabric at the seams, and here the fire resisting properties of the glove are impaired, so that it fails adequately to protect the wearer.

Hitherto attempts to solve the problem of knitting articles from asbestos yarn on a machine have been directed, but so far without success, towards so improving the machine that the material will no longer tear under the stresses imposed during knitting. The present invention provides a successful solution to the problem by 20 modifying the character of the yarn itself as distinct from the machine.

The invention provides a method of manufacturing knitted articles from asbestos yarn, which consists in first wetting the yarn with a non-oleaginous liquid lubricant which, without deleteriously affecting the structure of the yarn, reduces its inherent tendency to tear to an extent sufficient to enable it to be knitted mechanically and then knitting the wet yarn to the desired form on a machine.

40 The preferred lubricant is soap solution, because of its cheapness and of the ease with which it can be removed from the article after the knitting operation is completed, i. e. by simply washing the article. Glycerine or substitutes therefore, in aqueous solution, may also be used, but soap is preferred, owing to its cheapness. As further examples of agents which can be used for lubricating the yarn may be mentioned aqueous solutions of starch and soda.

45 The soap can be applied to the yarn in a very simple manner. The bobbins on which the yarn is spun may simply be dipped in a bath containing a soap solution, preferably of about 5% strength. The soap solution can, for example,

be made by dissolving 1 kg. of soft soap containing 45% fat in 8 litres of warm water. The bobbins are then placed in position on the machine, preferably after squeezing them to remove excess solution, and the knitting operation carried out 5 before the yarn has had time to dry.

Alternatively the soap solution may be applied to the yarn at the point of knitting by allowing a stream of soap solution to flow over the yarn as it passes to the needles.

10 Some methods of carrying the invention into effect will now be described in detail, by way of example, with reference to the accompanying drawings, in which

15 Figs. 1, 2 and 3 are diagrammatic views of three different methods of treating the asbestos yarn so as to render it susceptible of being knitted on a machine; and

20 Fig. 4 shows a glove knitted on a machine from asbestos yarn treated in accordance with the present invention.

25 As explained above, the yarn can be treated with the lubricant, e. g. soap solution, by simply dipping the bobbin on which the yarn is wound in a bath of soap solution. The yarn may however have the soap solution applied continuously as indicated at Figs. 1-3 of the drawings.

30 In the arrangement shown in Fig. 1 the yarn 20 is unwound from a bobbin 10, and led over a guide roller 13, under a roller 11 rotatably mounted in a bath 12 containing a soap solution, 35 over a guide roller 14 and through a guide 15 to the needles 16 of a knitting machine.

35 The arrangement shown in Fig. 2 is similar but in this case the yarn 20 does not actually pass into the bath, but between rollers 11, 21, the lower of which rotates in the bath and moistens the yarn with soap solution.

40 In the arrangement shown in Fig. 3, the yarn 20 receives a stream of soap solution from a tap 17 just before reaching the guide 15, a funnel 18 serving to reserve the excess of soap solution.

45 By adopting the invention, asbestos articles of clothing of greatly improved properties can be manufactured, because owing to the fact that they are made by knitting instead of weaving they possess a greatly improved flexibility. This is of great importance in the case of gloves which are intended to be worn when handling hot materials. Thus knitted gloves manufactured according to the invention can be readily used for unscrewing red hot nuts. Again asbestos suits for firemen as hitherto made have been so stiff and rigid as seriously to interfere with the free movement of the wearer. When knitted mechanically by 50

55

the method according to the invention, however, the suit is extremely pliable and yields readily to movements of the person wearing it. Moreover there is no necessity to provide sewn seams, 5 as the contacting edges of the knitted fabric can be knitted together so as to leave no apparent seam at all. Obviously the manufacture of knitted articles on a machine as distinct from by hand effects a vast saving in cost, as long 10 lengths of endless knitted fabric can be made (e. g. when making gloves) and subsequently subdivided into the individual articles.

In addition to garments (e. g. gloves, caps, suits, aprons and the like), the method according to the 15 invention can be applied to the manufacture of a great many other asbestos articles, e. g. packing and jointing rings, clutch and brake linings, belting, and fireproof curtains. Knitted curtains have the great advantage over woven curtains 20 that they can be more easily rolled up and do not develop cracks when so rolled. Moreover the knitted material can readily be impregnated with suitable materials, as is for example required in the case of brake linings.

25 The invention includes, in addition to the method described above, knitted articles made by knitting asbestos yarn on a machine. When knitting gloves, for example, the glove is knitted in the form of a continuous tube comprising a series 30 of sections joined end to end by portions representing the fingers of the glove. The tube is divided, after knitting, into elements each representing a glove and the contacting edges of the fingers are united by knitting so as to leave no 35 seam. Similarly other articles of clothing, e. g. jackets, trousers and the like may be knitted in

the form of a continuous tube, which is subsequently divided to give the individual garments. It is deemed unnecessary to describe in detail the knitting operation which is conducted in a manner similar to that adopted for the continuous 5 knitting of garments from wool and other textile materials.

Gloves can also be knitted from asbestos without separate fingers, but merely with a separate thumb piece, which is knitted to the body portion of the glove at the root of the thumb and also knitted at the end of the portion to receive the four fingers without leaving seams which would be insufficiently resistant to heat. Such a glove is shown in Fig. 4, in which 19 represents 10 the thumb piece, 22 the portion to receive the four fingers, and 23, 24, 25 the hand knitted 15 seams which close the glove.

It is to be understood that the term "asbestos 20 yarn" as used herein includes not only yarn made from pure asbestos, but also mixed asbestos yarns (e. g. yarn made from a mixture of asbestos and cotton) and asbestos yarn with an insertion of cotton, brass wire or other material. Such 25 yarns cannot ordinarily be knitted mechanically owing to the asbestos tearing, but they can readily be rendered susceptible to mechanical knitting by the process according to the invention.

What I claim as my invention and desire to 30 secure by Letters Patent is:

A method of manufacturing knitted articles 35 from asbestos yarn, which consists in first wetting the yarn with an aqueous soap solution and then knitting the wet yarn to the desired form on a machine.

THEODOR KRASSELT. 35
